SPRAYING DEVICE.

1,300,014.

Specification of Letters Patent.

Patented Apr. 8, 1919.

Application filed May 31, 1917. Serial No. 171,890.

To all whom it may concern:

Be it known that we, JAMES W. RANSON and OTTO A. GERSTUNG, both citizens of the United States, residing at Chicago, in the 5 county of Cook and State of Illinois, have invented certain new and useful Improvements in Spraying Devices, of which the following is a specification.

Our invention relates to improvements in 10 spraying devices, and is particularly suited for use as a hand apparatus for spraying surgical and medicinal preparations.

One of the objects of the invention is to 15 provide an improved spraying device particularly suitable for spraying liquids which occur in solid form at ordinary atmospheric temperatures. Subsidiary objects of the invention are to provide an arrangement of the class described, so organized that substantially the full amount of the charge may 20 be utilized; to provide an improved arrangement of the class described capable of being operated by hand; to provide an improved construction so organized that pressure may 25 be introduced into the apparatus through the handle of the device; to provide an improved construction capable of being manipulated conveniently and efficiently without the expenditure of undue effort or concentration 30 on the part of the operator; to provide a construction of the class described which embodies very few parts, and those of simple and practical design; to provide an improved construction which shall be economical 35 to manufacture and yet extremely efficient in use and economical to operate and maintain; and, in general, to provide an improved spraying device of the character referred to.

40 In the drawings—

Figure 1 is a side view of the complete device;

Fig. 2 is a longitudinal vertical section of the principal parts of the device; and

45 Fig. 3 is a section taken on the line 3—3 of Fig. 2.

Referring to the drawings, 10 represents a longitudinal casing or tank of fairly heavy brass or other metal having a reasonably 50 high heat conductivity. The construction of the said tank does not involve any novel mechanical problem. It may be made from a single section of tubing with the bottom 11 and top 12 separately made and subsequently 55 united to the body section; or one of the

parts 11 and 12 may be formed from a suitable blank integral with the cylindrical part of the casing. We prefer to equip the top 12 of the casing 10 with a threaded neck part 13 upon which is screwed a filling cap 14, a 60 suitable annular gasket 15 being interposed between the neck 13 and the cap 14 to form a hermetic closure.

Describing the nozzle and associated parts, 16 is a brass sleeve, the outer end of which 65 is threaded, as shown at 17, and screwed into the side of the tank 10 where the shoulder 18 bears against the inside surface of the tank wall. A nut 19 screwed onto the outside of the threaded portion 17 locks the sleeve 16 70 securely in place. It is understood that in order to make a perfectly air-tight fit, solder or other suitable means may be employed. On the nose of the threaded portion 17 is also screwed the nozzle proper 20, the 75 latter having its end curved, as shown at 21, and perforated with a small inclined port 22, the inner end of said port being substantially coincident with the axis of the tube 16.

The liquid, which is introduced into the 80 casing 10 through the filling hole at the top of the tank, is conducted to the vicinity of the nozzle 20 by means of a small L-shaped copper tube 23, the upper horizontal limb of which is a rather loose fit in the longitudinal 85 hole drilled in the sleeve 16. Preferably, the end of the feed tube 23 is rounded slightly, as shown at 24, and perforated with a hole smaller in diameter than the interior diameter of the tubing, so as to deliver the liquid 90 in a small jet. The lower end of the feed tube 23 is open, as shown in Fig. 2, and extends almost to the bottom of the tank 10, the horizontal arm of the tube being of such length that the end 24 occupies a position 95 somewhat in the rear of the orifice 22. Rearward movement of the feed tube 23 in the sleeve 16 is prevented by means of a small oblique guard plate or shield 25, one end of which is suitably secured to the top of the 100 sleeve 16.

Pressure to operate the device, in the present instance, is supplied in the form of air by means of an ordinary bicycle pump 26,—that is to say, a pump used for inflating 105 pneumatic tires of bicycles or motorcycles. The said pump 26 is preferably fitted at its discharging end with a plug 27 threaded internally to screw onto a threaded neck 28 of a fitting 29 threaded on its inner end, as 110

shown at 30, to screw into a nut 31 soldered to the inside of the tank and to the inner tubular extension 32 of the fitting 29. The outer end of the fitting 29 has a shoulder or flange 33 to facilitate the mounting of said fitting in the side of the tank and the fitting as a whole is drilled out longitudinally, as shown at 34, the inner end of the hole in the fitting being beveled at a suitable angle, as shown at 35, in order to provide a valve seat for the valve ball 36, constituting in effect a check to prevent egress of air. The inner end of the tubular extension 32 is flanged over slightly, as shown at 37, the 10 end of the tube being open; and, if desired, action of the check ball 36 may be made somewhat more positive by means of a light coil spring 38.

The operation of the device is simplicity itself. The liquid to be sprayed is inserted into the tank by removing the filling cap 14, which is subsequently screwed down tightly so as to seal the tank. The main body of the tank 26 constitutes a handle by which the device may be manipulated or pointed to spray material upon any desired area, while the handle 39 of the pump is moved back and forth to reciprocate the pump spindle 40 in the usual manner so as to charge the tank with air under considerable pressure. By reason of the hole 22 being open, the air rushes out of the nozzle through the small crevice between the feed tube 23 and the sleeve 16, and, owing to the friction of the air through said restricted passageway causing a distinct loss of pressure, liquid is forced up the tube 23 and out of the perforation in the end 24 of the feed tube. The compressed air, as it passes the end 24 on its way to the nozzle, atomizes the jet of liquid issuing from the feed tube and the air charged with the particles of liquid thus produced issues from the nozzle aperture 22 in a cone-shaped spray 41.

It will be observed that the axes of the pump 26 and of the nozzle are in alignment and that the feed tube 23 is loosely supported in the sleeve 16 so that it may rotate or swing in the sleeve 16 when the tank 10 is tilted or swung about the axis of the pump 26. This permits the lower end of the feed tube 23 to, in effect, "follow" the liquid in the bottom of the tank so that practically the entire contents may be discharged, even though the tank be held in an inclined position. The object of extending the tubes 16 and 32 toward the axis of the tank for a considerable distance from the side of the tank, is to prevent liquid from flowing into the ends of said tubes when the device is held with the handle in inclined position. The guard 25 is also made of sufficient dimensions to prevent the pump from throwing liquid into the open end of the tube 16 and thereby causing the nozzle to spit with-

out atomizing the liquid. In the particular embodiment shown, it will be observed that the nozzle aperture 22 is inclined so as to deliver the spray in a direction at an angle to the axis of the nozzle tube 16 and the axis of the pump or handle. This is an important feature in certain cases, where the spray must be directed under, over, or onto the side of an object. It will therefore be manifest that the swinging possibility of the feed tube 23, in order to enable it to "follow" liquid as the device is rocked on the axis of the pump 26 to direct the spray into different directions, is an important and highly desirable feature of our invention. 80

A device of the general construction indicated herein is of particular value in spraying liquids formed by heating above the melting point materials which are normally solid at ordinary atmospheric temperatures. 85 For instance, there has recently been discovered for surgical purposes a method of treating burns, which consists in applying to the surface of the burn a coating of more or less inert wax-like material which, in order to 90 secure the best results and to prevent unnecessary pain, should preferably be applied in the form of a spray. The spraying of such material, which has a melting point considerably higher than the temperature of the body, obviously presents more or less difficulty, since the fluid material and the various parts with which it may come in contact before being sprayed onto the burn, must be maintained at a temperature higher than 95 that of the melting point of the substance. In the construction herein described, no difficulty is encountered in this connection, for the reason that the principal parts of the device are preferably made of comparatively 100 thick metal having a high heat conductivity, such as brass or copper, such metal also being capable of receiving a polished nickel coating to good advantage, which also prevents radiation of heat and enables the 105 liquid to maintain itself in melted and sprayable condition for long periods. For instance, with a tank only three inches in diameter, no additional heat need be supplied for a period of thirty minutes, or even longer 110 in certain cases.

The device also has another important advantage, in that the tank may be reversed after it has been filled with the hot liquid so as to permit the liquid to warm up the various parts at the top of the apparatus, thus effecting a saving of time which would otherwise be needed to permit the conductivity of the metal to bring such parts to the temperature required to prevent danger of freezing. 120

It is of course understood that the detailed description refers to a specific application of our invention, the scope of which is not necessarily limited thereby but must be de- 125 130

terminated by reference to the appended claims.

We claim—

1. In a spraying device, the combination 5 of a cylindrical tank having its axis vertical, a nozzle projecting outwardly from one side of said tank, a tube projecting inwardly into the tank and constituting a conduit for conducting the air to said nozzle from the interior of the tank, a feed tube open at both ends, having one end extending into said air tube for a substantial percentage of its length and the other end bent down to dip into liquid contained within said tank and adapted 10 to swing about the axis of the air tube, and means for forcing air into said tank.

2. In a spraying device, the combination 15 of a cylindrical tank having its axis vertical, a nozzle projecting outwardly from one side of said tank, a tube projecting inwardly into the tank and constituting a conduit for conducting air to said nozzle from the interior of the tank, a feed tube open at both ends, having one end extending into said air tube 20 for a substantial percentage of its length

and the other end bent down to dip into liquid contained within said tank and adapted to swing about the axis of the air tube, means for forcing air into said tank, and a guard provided on the inner end of said air tube to maintain said feed tube in position. 30

3. In a spraying device, the combination 35 of a cylindrical tank having its axis vertical, a nozzle projecting outwardly from one side of said tank, a tube projecting inwardly into the tank and constituting a conduit for conducting air to said nozzle from the interior of the tank, a feed tube open at both ends, having one end extending into said air tube for a substantial percentage of its length 40 and the other end bent down to dip into liquid contained within said tank and adapted to swing about the axis of the air tube, means for forcing air into said tank, and a guard provided on the inner end of said air tube to maintain said feed tube in position 45 and arranged to protect the open end of the air tube.

JAMES W. RANSON.
OTTO A. GERSTUNG.
